TEMPERATURE CONTROLLED SWITCH

Judson W. Wright, Detroit, Mich.

Application March 1, 1935, Serial No. 3,796

5 Claims. (Cl. 200—137)

This invention relates to temperature controlled switches and the object of the invention is to provide a switch for use in connection with a hot water tank and arranged to turn off or on in accordance with the expansion or contraction of the tank.

Another object of the invention is to provide a temperature controlled switch having a longitudinally movable rod operating through a toggle joint to actuate the switch.

A further object of the invention is to provide an arm pivotally supported on the top of the tank in which one end of the arm is connected to the bottom of the tank and the other end of the arm is connected to the temperature controlled switch which is connected to the bottom of the tank so that expansion of the tank to a predetermined extent will move the temperature controlled switch to the open position and contraction of the tank will allow movement of the switch to the closed position.

These objects and the several novel features of the invention are hereinafter more fully described and claimed and the preferred form of construction by which these objects are attained is shown in the accompanying drawing, in which—

Fig. 1 is an elevation of a hot water tank equipped with my temperature controlled switch.

Fig. 2 is an enlarged section taken on line 2—2 of Fig. 1 and showing the switch mechanism.

Fig. 3 is a section taken on line 3—3 of Fig. 2.

Fig. 4 is an enlarged section taken on line 4—4 of Fig. 2.

The switch comprises a housing 1 which may be octagonal in form, as shown in Fig. 2, and which may be provided with a cover 2, a portion of which is shown in Fig. 2. The housing 1 is provided with a lug 3 and a screw 4 shown in Fig. 3 extends through the lug 3 and is threaded into the bottom of the housing. An arm 5 is pivotally mounted on the screw 4 and the end of the arm 5 opposite the screw 4 is provided with a contact member 6, shown in Figs. 2 and 4, which is secured in the end of the arm 5 and insulated therefrom by the insulator 7. A wire 8, shown in Fig. 2, is connected to the contact 6 and this wire extends through an insulator 9 in the wall of the housing and is connected in the electric circuit to be controlled. A bracket 10 is secured to the wall of the housing 1 on the opposite side of the housing from the lug 3 and this bracket provides a support for the arm 11 which is pivotally connected to the bracket 10 at the point 12. The end of the arm 11 opposite the pivot 12 carries a screw 13 which extends through a slot 14 in the arm 5.

A vertical rod 15 is movable longitudinally through the housing 1 and the rod 15 is secured to the arm 11 by the screw 16 which extends through the arm 11 and is threaded through the rod 15, as shown more particularly in Fig. 3. The lower end of the rod 15 extends below the housing and a coiled spring 17 is positioned about this lower end and may be adjusted in tension by means of the nut 18 threaded onto the lower end of the rod.

The bracket 10 carries an insulation block 19 in which a contact screw 20 is threaded and the upper end 21 of this contact screw is adapted to be contacted by the contact 6 carried in the arm 5. A wire 22 leads from the contact screw 20 through an insulator provided in the housing wall 15 and is connected into the control circuit. The cover 2, as shown in Fig. 3, is provided with a slot 23 so that the cover 2 may be slipped underneath the head of the screw 4 and the opposite side of the cover is held in place by a screw 24 shown in Fig. 2 which is threaded into the lug 25 extending inwardly from the housing wall. As shown in Fig. 3, a coiled spring 27 is positioned about the screw 4 and one end of the spring is anchored in the housing 1 while the other end of the spring is secured beneath the head of the screw 13. This spring urges the arm 5 to turn to position to bring the contact 6 into engagement with the end 21 of the contact screw 20.

As shown in Fig. 1, an arm 26 is pivotally mounted in a bracket 27 on the pipe 28 extending from the top of the hot water tank 29. The end 30 of the arm 26 is connected by means of a wire 31 with a clip 32 which is hooked under the bottom edge of the tank 29, while the opposite end 33 of the arm 26 is connected by means of a wire 33 to the turnbuckle 34 which in turn is connected to the upper end of the rod 15. A wire 35 shown in Figs. 1 and 2 is connected to the housing 1 behind the rod 15 and the lower end of the wire 35 is provided with a clip 36 engaging under the lower edge of the tank.

In operation, when the tank is cold, the turnbuckle 34 is adjusted to allow the spring 17 to draw the rod 15 downwardly and allow the contact 6 to engage the point 21 of the contact screw 20. This allows current to flow through the wire 8, through the contacts 6 and 21 to the wire 22 and while not here shown, this circuit is connected to operate the gas valve for heating water. As the water in the tank becomes warm, the tank is warmed and as the tank becomes warmed, it expands slightly moving the pivot 37 for the arm 26 upwardly in relation to the temperature controlled switch. This is due to the 55

fact that the opposite ends of the arm 28 are anchored to the bottom of the tank and any expansion of the tank will cause movement of the pivot 37 upwardly in relation to the clips 32 and 38 at the bottom of the tank. Due to the wire 34, this upward movement of the pivot 37 causes the arm 28 to turn slightly in a counter-clockwise direction thus raising the rod 15 against the tension of the spring 17 and by means of the screw 16 the rod 11 is turned on the pivot 12. As the rod 11 is turned, the screw 13 therein turns the arm 5 on the pivot 4 against the tension of the spring 47 to quickly move the contact 6 away from the contact point 21 thus quickly breaking the circuit without drawing an arc between the contact points. As the hot water is used out of the tank, the tank will cool off and as it cools and contracts, the arm 28 will turn in a clockwise direction on the pivot 37 and this turning movement will be taken up by the spring 17 to move the rod 15 downwardly.

As the rod 15 is moved downwardly, the arm 11 is turned downwardly and by means of the screw 13 riding in the slot 14 this toggle action quickly moves the arm 5 assisted by the spring 47 to bring the contact 6 back against the contact point 21 and re-establish the circuit. By means of the turnbuckle 34, the amount of expansion required to operate the temperature controlled switch may be accurately adjusted so that the tank may be one-half or three-quarters full of water before sufficient expansion has occurred to operate the switch.

From the foregoing description it becomes evident that the device is very simple and efficient in operation, will not easily get out of order, is composed of few parts and provides a device which accomplishes the objects described.

Having thus fully described my invention, its utility and mode of operation, what I claim and desire to secure by Letters Patent of the United States is—

1. In a temperature controlled switch, a container, an arm pivotally supported on the top of the container, means connecting both ends of the arm with the bottom of the container, a pressure switch included in one connecting means and including a housing, a rod movable longitudinally through the housing, a spring tending to move the rod in one direction, the connecting means being connected to one end of the rod to move the rod against the tension of the spring, a pair of toggle arms movable by the rod, a contact carried by one of the toggle arms, a contact in the housing, the contacts being connected into an elec-

trical circuit and a turnbuckle for adjusting said connecting means above the temperature controlled switch.

2. In a temperature controlled switch, a container, a support extending from the top of the container, an arm pivotally mounted on the support, a wire connecting one end of the arm with the bottom of the container, a temperature controlled switch including a housing connected to the bottom of the container, a rod movable longitudinally in the housing, a toggle switch movable to open position upon movement of the rod in one direction and movable to the closed position upon movement of the rod in the opposite direction, a spring tending to move the rod to close the switch and means connecting the rod with the opposite end of the arm.

3. In a temperature controlled switch, a container, a support extending from the top of the container, an arm pivotally mounted on the support, a wire connecting one end of the arm with the bottom of the container, a temperature controlled switch, a wire connecting the temperature controlled switch to the bottom of the container, the pressure switch being provided with a movable operating member, a wire connecting said operating member with the opposite end of the arm, the arrangement being such that as the container expands the temperature controlled switch is moved to the open position and as the container contracts the temperature controlled switch is moved to the closed position.

4. In a temperature controlled switch, a container, a support extending from the top of the container, an arm pivotally mounted on the support, means connecting one end of the arm with the bottom of the container, a temperature controlled switch, means connecting the temperature controlled switch with the bottom of the container and means connecting the temperature controlled switch with the opposite end of the arm whereby expansion or contraction of the container moves the arm pivot and arm to open or close the temperature controlled switch.

5. In a temperature controlled switch, a container, an arm pivotally supported on the top of the container, means connecting the opposite ends of the arm with the bottom of the container, one means including a switch, spring means tending to move the switch to the closed position and the arrangement being such that as the container expands the arm is turned on its pivot to move the switch to the open position against the tension of said spring.

JUDSON W. WRIGHT.
